[57] CLAIM

The ornamental design for a gas fired poultry brooder
with ceramic-type radiant, as shown and described.

DESCRIPTION

FIG. 1 is a front perspective view, viewed from below,
of a gas fired poultry brooder with ceramic-type radi-
ant, showing my new design;

FIG. 2 is a right side elevation view thereof;

FIG. 3 is a front elevation view thereof;

FIG. 4 is a left side elevation view thereof;

FIG. 5 is a rear elevation view thereof;

FIG. 6 is a top plan view thereof; and

FIG. 7 is a bottom view thereof.
